UNITED STATES PATENT OFFICE.

JONATHAN PETERSON, OF BROOKLYN, NEW YORK.

MACHINE FOR INCISING PLUG-TOBACCO.

1,266,309.

Specification of Letters Patent. Patented May 14, 1918.

Continuation of application Serial No. 130,822, filed November 11, 1916. This application filed September 28, 1917. Serial No. 193,689.

To all whom it may concern:

Be it known that I, JONATHAN PETERSON, a citizen of the United States, residing at Brooklyn, in the county of Kings and State of New York, have invented new and useful Improvements in Machines for Incising Plug-Tobacco, of which the following is a specification.

This invention relates to a machine for producing a plug of tobacco such as is set forth in my Patent No. 1,217,496, dated February 27, 1917, and furthermore, the present application is in the nature of a continuation of my application for machine for incising plug tobacco, filed November 11, 1916, Ser. No. 130,822, patented Dec. 4, 1917, Patent No. 1,248,540.

In my Patent No. 1,217,496, aforesaid, I have shown and described a plug of tobacco which is divided into small sections or portions of a size suitable for chewing, for instance, by cutting or incising the plug from opposite sides in such manner that a cut or incision on one side of the plug terminates short of, or does not meet an adjacent cut or incision on the opposite side of the plug, so that a web or unitary strata results which extends substantially throughout the center or centrally of the plane of the plug, and the various sections formed or marked out by the incisions, will be united by this web. When the user desires a portion of the tobacco plug, it is only necessary, with the exercise of but very little force or effort, to break or separate such piece from the remainder of the plug, the action of bending or breaking of course tearing that portion of the web which unites the particular section to the plug. Such an incised plug is illustrated in Fig. 4 of the present drawings.

In my co-pending application, No. 130,822, aforesaid, I have shown and described, and broadly claimed, a machine for producing such a plug, and therefore, in the present application I will direct the claims to the specific type of machine shown herein, inasmuch as I have included in said earlier application claims generic to both types of machines.

In the present instance, it is my purpose to provide a machine which will embody the desired features of simplicity, compactness, durability and strength, and through the agency of which plugs of the character de-

sired may be rapidly, continuously and economically produced in great quantities. Furthermore, the present machine will operate with great certainty and accuracy, the various parts going to make up the machine coöperating positively and in proper timed relation to form the incisions or cuts at the desired points in the plug.

With the above recited objects and others of a similar nature in view, my invention consists in the construction, combination and arrangement of parts set forth in and falling within the scope of the appended claims.

In the accompanying drawings:

Fig. 1 is a vertical longitudinal sectional view taken through a plug slitting machine embodying my invention.

Fig. 2 is a transverse sectional view taken on the line 2—2 of Fig. 1, looking in the direction of the arrows.

Fig. 3 is a top plan view of the machine.

Fig. 4 is a perspective view of a slit or incised plug of tobacco, such as is produced by the machine, one section of the plug being removed or torn away.

Referring now to the accompanying drawings in detail, the standards of the machine are shown at 1 and support a bed-plate 2 having mounted thereon a frame A which supports the operating mechanism of the machine. Mounted on this frame A is a table or platform 3 adapted to receive the plugs to be cut, said plugs being shown at P in Fig. 1. The forward end of this table 3 is preferably attached to vertical side bars 4 forming a part of the frame A while the rear end of the table is supported by suitable braces 5 extending between the bed-plate and the bottom of the table. In order to feed the plugs P from the table to the machine, any suitable mechanism may be employed, and in the present instance I make use of a sliding pusher bar 6 composed of spaced parallel slats, one lying above and the other beneath the slotted bottom board 7 of the table, as shown in Figs. 1 and 3. To reciprocate the pusher bar 6, I connect the ends of the lowermost slat thereof, as at 8 to the pusher rods 9, the opposite ends of said rods being pivoted as at 10, to the links 11, connected at 12 with the upper ends of the angular arms 13 of the rocking segmental plug clamping and feeding member

B, by the ends of the tie rod 28. There are two of these rocking segmental plug clamping members, the other being indicated by the letter C, and these segmental clamping members are formed with convex plug-clamping faces which are oppositely disposed, and these clamping members are geared together as hereafter described, so that as the plugs are pushed one at a time 10 from the table 3, they drop downward and are directed by a guide formed of the curved arms 13 and 13' and the deflector board 14 at the lower ends of the arms 13 to a position to be clamped and fed by the oppositely 15 disposed convex faces of the clamping members and to be cut by the cutters. Any suitable means may be employed for guiding the plugs to the machine other than that shown herein.

20 The clamping member B comprises a pair of angular arms 12 formed intermediate their lengths with the bearing collars 15, by means of which the arms are mounted upon and made fast with the rock shaft 16. This 25 rock shaft extends transversely of the machine above the bed-plate thereof and each end of such shaft is journaled in a sleeve bearing 17 forming the upper end of a yieldingly mounted post 18. Each post 18 is 30 bifurcated at its lower end as at 19 to fit over a web 20 forming a part of the frame A and at its bifurcated portion is pivoted as at 21 to such web. Each of such arms 18 is also formed with a lateral extension 22 bored for the reception of the bolt 23 which passes loosely therethrough, a spring 24 being coiled about the shank of the bolt and interposed between the extension 22 and the block 25 bolted as at 26 to the adjacent part 35 of the frame of the machine. A nut 27 is threaded on to the end of the shank of the bolt which projects above the extension 22, with the result that the arm 18 is tensioned, and such tension may be adjusted as desired.

40 Furthermore, these yielding arms 18 by means of the pivot mounting and tension spring just described, will yield to the desired degree when necessary to permit the passage between the clamping members B and C of plugs of different thicknesses. The 45 alining ends of the arms 12 are connected by horizontal tie-rods 28, these tie-rods passing through and supporting the abutting heads 29 of the series of curved or bowed, 50 spaced slats 30, which form the plug-engaging section of the plug clamping member B. One of the arms 12 carries a segmental rack gear 31, which meshes with a similar but 55 oppositely disposed rack gear 32 of the companion clamping member C. Like the clamping member B this clamping member C includes a pair of angular arms 12', one of which carries this segmental rack gear 32. These arms 12' are also formed with collars 60 15' intermediate their ends by means of

which the arms are mounted upon and made fast with the rock shaft 16', the latter being journaled in sleeve bearings 17' formed on the frame A. The alining ends of these arms 12' are also connected by horizontally extending tie-rods such as is shown at 28', these rods passing through and supporting the abutting heads 29' of a series of spaced, bowed or curved slats 30', which slats form the operating section or face of the clamping member C, as shown in Fig. 2. Curved or semi-circular plates 33 are attached to the arms 12' or at each end of the clamping member C and form braces for such member, as well as constituting guard plates for 80 the cutting mechanism.

In order to actuate the clamping members B and C, or to impart a rocking plug-feeding and clamping action thereto, any suitable train of power mechanism may be 85 employed. In the present instance, the power shaft 34, driven from the belt pulley 35, carries at one end a crank 36 which is in turn connected with a crank arm 37 through a link 38. The crank arm 37 is made 90 fast with one end of the shaft 16' of the clamping member C, and the result is that as the power shaft turns a rocking motion will be imparted through the link connection to the shaft 16' in turn rocking the 95 clamping member C, which being geared with the clamping member B will rock the latter back and forth, so that, as will be understood by reference to Fig. 1, as the plugs are fed or dropped downward between the two clamping members B and C, they will be gripped by the slatted walls or sections of these clamping members, and fed past the two cutting mechanisms D and E, at which time the cutting or incising of the 100 plug takes place.

The cutting mechanism D which is associated with the clamping member B comprises in the present instance a plurality of sets of circular cutter disks 36 mounted 110 upon a rotating shaft 37, the disks of each set being held in suitable spaced relation by means of small collars 38. In the present instance, as will be seen by reference to Fig. 2, there are three sets of these cutter disks 36, 115 there being six disks to each set, and one set is spaced apart from the other by spacing collars 39, but it will of course be understood that there may be any number of these disks arranged in any desired manner. Suitable retaining nuts 40 are adjustable on the threaded section 41 of the shaft 37 so that proper adjustment and positioning of the cutter disks may be made, as will be readily understood. The ends of the shaft 37 are 120 mounted in eccentric bearing sleeves 42, which are fitted into the bearings 43, forming part of the frame A and by turning these eccentric sleeve bearings, the shaft 125 may be adjusted to adjust the cutters rela- 130

tive to the clamping face or section of the member B, or relative to the descending plug. The circular blades of the cutters 36 lie in the spaces between the slats 30 so as 5 to project slightly beyond the outer clamping faces of the slats or into position to cut plugs, as will be clearly understood by reference to Fig. 3, and by adjusting the shaft with the eccentric sleeve bearings, as before 10 mentioned, the cutting edges of the blades may be caused to project through the slats to a greater or lesser degree, as may be desirable.

Likewise, the cutting mechanism E is in 15 the nature of the gang cutter, that is to say on the rotary cutter shaft 37 I mount a plurality of spaced rotary cutters 36' corresponding in number and arrangement to the cutters 36 and positioned so as to coöperate 20 therewith in the cutting or incising of the plug, these cutter disks 36' being spaced by the collars 38' and 39', and are held in position and adjusted by the nuts 40' threaded on the threaded sections 41' on the shaft 37'.

25 Likewise, the shaft 37' is mounted in eccentric bearings 42' fitted in the bearings 43' forming an adjacent part of the frame A. In other words, these two sets of cutting mechanisms, D and E, are similar in structure, and arrangement and the like, one set 30 operating on one side of the plug while the other set operates on the opposite side, and in the operation of the present machine for the purposes of forming a plug, such as is shown in Fig. 4, care should be taken that 35 the two cutting mechanisms should be so adjusted relative to each other and relative to the segmental clamping members B and C with which they are associated, so as to

40 cut the plug on both sides, but not so deep as to cause the cuts to meet or to entirely sever the plug sections. The cutter shafts 37 and 37' may be driven in any suitable manner, and in the present instance I mount 45 upon the power shaft 34 the sprocket 44 driving an endless chain belt 45, this belt passing over an idler 46, thence around the sprocket 47 upon the shaft 37 of the cutting mechanism D, thence over a sprocket 47' of 50 the cutting mechanism E, the endless chain being driven, as shown in Fig. 1, so that the shafts 47 and 47' will of course be driven in opposite directions to cause the cutters of the mechanisms D and E to rotate in opposite directions, while cutting the plug.

55 As the plug passes down and is clamped by the clamping members B and C it is fed through and to these cutters where it is incised or cut on both sides to produce the plug shown in Fig. 4, and the plug so incised or cut, then drops by gravity onto the concave delivery chute F which is formed of a series of curved, spaced slats 48 fastened together by tie-bars 49 and 50, the plugs sliding down 60 this chute to a suitable point of discharge. 65

As will be seen by reference to Fig. 1, the plugs may be so placed on table 3 that with the reciprocation of the pusher bar 6, a rear plug will push a forward plug down the guideway to position to be operated upon 70 by the convex faces of the clamping members B and C, by which the plug will be carried into position to be cut by the rotary cutters, and the depth of the cuts or incisions made in the plug may be regulated by adjusting 75 the cutter shafts, as hereinbefore described. The operation of cutting or incising the plugs may be carried on with great rapidity and accuracy as to depth and location, the cutters being kept clean or free from shreds 80 of tobacco and the like by small, flexible scrapers 51. It will further be noted that plugs of varying thickness may be uniformly operated upon by the machine, as owing to the yielding nature of the mounting of the clamping member B, the supports 18 for the latter will yield when a thick plug is passing therethrough, thus obviating the jamming of the plug while when a relatively thin plug is passing through the 90 machine these arms 18 will be forced by the springs in the opposite direction to throw the clamping section or face of the member B toward the member C to insure the proper gripping of the plug. 95

As heretofore mentioned, and as will be noted by reference to Figs. 2 and 3, the cutters are in the nature of gangs, each comprising a plurality of spaced cutting disks. As is well known, the ordinary tobacco plug 100 as packed for shipment to the retailer is in the form of an oblong or rectangular bar or piece, and when cutting such a plug with this machine, it may be fed broad-side to the cutters so that all of the sets will operate simultaneously upon the plug, thereby making the incisions throughout the entire width of the plug. Or if desired, as in making cross cuts on the plug, or forming the incisions lengthwise thereof, the plug 105 may be fed between a single set of opposing cutters. In other words, the plug may be so fed as to cause all of the cutters to simultaneously operate thereon, or may be fed so as to simply cause an opposing pair of sets 110 of cutters to operate on the plug. 115

While I have herein shown and described one particular embodiment of my invention, I wish it to be understood that I do not confine myself to all the precise details of construction herein set forth by way of illustration, as modification and variation may be made without departing from the spirit of the invention or exceeding the scope of the appended claims. 120

125 What I claim is:

1. In a machine for incising plug tobacco to provide a plug having a plurality of integrally united sections, the combination with a pair of rocking members having op- 130

- posed convex clamping faces operative to clamp and release a plug therebetween, of cutting mechanism located adjacent said clamping members and constructed to incise the plug while such plug is clamped between the convex faces of said members.
2. In a machine for incising plug tobacco to provide a plug having a plurality of integrally united sections, the combination with 10 a pair of curved, rocking clamping members having convex clamping faces and geared together to move into and out of plug-clamping relation and clamp a plug between their convex faces, and cutting mechanism 15 mounted adjacent the clamping members and constructed to operate upon a plug of tobacco while the latter is held between the convex faces of the clamping members, to provide a plurality of spaced incisions extending from the face of the plug partly 20 therethrough.
3. In a machine for incising plug tobacco, the combination with a pair of rocking, segmental clamping members having opposed 25 convex clamping faces adapted to clamp and release a plug of tobacco, of rotary cutters mounted adjacent the clamping members and constructed to operate upon a plug of tobacco while the latter is held between the 30 convex faces of the clamping members to provide a plurality of spaced incisions in the face of the plug.
4. In a machine for incising plug tobacco, the combination with a plurality of rocking, 35 segmental clamping members having convex clamping faces and geared together and adapted to clamp and release a plug therebetween, of a plurality of gangs of rotary cutters located adjacent the clamping members and adapted to incise a plug while the 40 latter is held between the clamping members.
5. In a machine for incising plug tobacco, the combination with a pair of rocking, 45 curved clamps, each having the plug clamping section thereof formed of spaced members, of cutters mounted adjacent the clamps and having portions projecting through the spaces between the members of the clamp 50 and adapted to operate upon a plug held between the clamps to form incisions in such plug.
6. In a machine for incising plug tobacco, a rocking, segmental clamp having a plug 55 clamping section formed of a plurality of spaced members, cutting mechanism projecting through the spaces between the members, and means for operating with the clamp for holding the plug in position to be 60 incised by the cutting mechanism.
7. In a machine for incising plug tobacco, the combination with a pair of rocking segmental clamping members having convex 65 clamping faces, of means for feeding a plug to the clamping members, and cutting mech-

anism operating upon the plug while clamped between the convex faces to form incisions in opposite faces of such plug.

8. In a machine for incising plug tobacco, the combination with a pair of rocking, segmental clamping members geared together and adapted to clamp and release a plug therebetween, of gangs of rotary cutters located adjacent the clamping members and projecting through spaces in the latter and 70 adapted to coöperate to cut incisions in opposite faces of the plug, and means for feeding plugs of tobacco to position between the clamping members to be gripped by the latter and operated upon by the cutters. 80

9. In a machine for incising plug tobacco, the combination with a pair of clamping members, a pusher device for feeding plugs of tobacco to the clamping members, cutting mechanism for making incisions in opposite faces of the plug through part of its thickness while such plug is clamped by the clamping members, a guide for feeding the plugs into position between the clamping members to be operated upon by the cutters 90 and means for delivering the incised plugs from the machine.

10. In a machine for incising plug tobacco, a yieldable support, a clamping member mounted to rock on said support, a second clamping member coöperating with the first mentioned clamping member, said clamping member having opposed convex clamping faces and adapted to clamp a plug of tobacco therebetween and means for incising the plug clamped by the clamping members. 95

11. In a machine for incising plug tobacco, the combination with a yieldably mounted rocking segmental clamping member, a second rocking segmental clamping member coöperating with the first mentioned clamping member and adapted to clamp a plug of tobacco, a plurality of gangs of rotary cutters located adjacent the clamping 110 members and adapted to incise opposite sides of the plug of tobacco held by the clamping members, and means for successively feeding the plugs to the clamping members. 105

12. In a machine for incising plug tobacco, the combination with a yieldably mounted rocking segmental clamping member, a second rocking segmental clamping member coöperating with the first mentioned clamping member and adapted to clamp a 115 plug of tobacco, a plurality of gangs of rotary cutters located adjacent the clamping members and adapted to incise opposite sides of the plug of tobacco held by the clamping members, and a pusher member pivotally 120 connected to one of said clamping members and adapted to feed plugs of tobacco into position to be clamped by the clamping members. 125

13. In a machine for incising plug to- 130

bacco, a plurality of segmental rocking clamping members geared together and adapted to clamp a plug therebetween, a feeder device connected with one of said 5 clamping members and adapted to feed the plugs to the clamping members, a guide for directing the plugs from the feeder device to the clamping members, a plurality of gangs of rotary cutters located adjacent the clamping members and adapted to project therethrough and to incise opposite faces of a plug held by the clamping members, means for adjusting the gangs of cutters, a delivery chute for conducting the incised plugs 10 from the cutters to a point of discharge, power transmission mechanism between the power shaft and one of the geared clamping members for imparting movement to the clamping members, and power transmission 15 mechanism interposed between the power shaft and the gangs of cutters for rotating said cutters in opposite directions.

14. In a machine for incising plug to-

bacco, a plurality of segmental rocking clamping members geared together and 25 adapted to clamp a plug therebetween, one of said clamping members being yieldably mounted to move toward and from the others, each of said clamping members having a plug clamping section comprising a 30 plurality of curved, spaced slats, a feeder device connected with the yielding clamping members and adapted to feed plugs to the clamping members, a plurality of gangs of 35 spaced rotary cutters located adjacent the clamping members and having the cutting edges thereof projecting through the spaces between the slats whereby to incise opposite faces of the plug held by the clamping members, and power transmission mechanism for 40 operating the clamping members and rotating the cutters.

In testimony whereof I have hereunto set my hand.

JONATHAN PETERSON.
